UNITED STATES PATENT OFFICE.

AUGUST RENZELBERG, OF NUEREMBERG, GERMANY, ASSIGNOR TO THE FIRM
REISSZEUGFABRIK EICHMULLER & CO., OF NUEREMBERG, GERMANY.

STRAIGHT-LINE GUIDE FOR THE HANDLES OF COMPASSES.

1,425,133.

Specification of Letters Patent. Patented Aug. 8, 1922.

Application filed October 15, 1921. Serial No. 508,047.

To all whom it may concern:

Be it known that I, AUGUST RENZELBERG, a citizen of the German Republic, and a resident of Nuremberg, Germany, have invented 5 a new and useful Improved Straight-Line Guide for the Handles of Compasses, of which the following is a specification.

Straight-line guides for the handles of compasses, in which on opening the compasses the handle adjusts itself by friction 10 into the middle line of the gap of the compasses are known. The invention consists in constructing the friction body as a rotary pin which is situated in the handle of the 15 compasses. The thus improved straight-line guide is illustrated, by way of example, in the accompanying drawing, in which similar letters of reference denote similar parts throughout the several views, and in which 20 Figure 1 is a front view of about the upper half of compasses constructed according to this invention, the uppermost portion, i. e. the handle, being shown in longitudinal section. Figure 2 is a side view of the parts 25 shown in Fig. 1. Figure 3 is an illustration similar to Fig. 1 and shows a slightly modified form of construction. Figure 4 is a side view of the parts shown in Fig. 3.

The heads 4 and 4' of the legs of the compasses lie side by side in a known manner 30 in the yoke 1. Upon the heads 4, 4' presses from above a rotary pin 2 which, preferably, is thickened at its lower end so as to form or to have a foot and I prefer to provide 35 this foot with a central cavity turning it into a circular inverted trough which contacts only at its rim with the two heads 4, 4'.

The pin 2 is loosely rotatable in the hollow handle which forms an extension of the 40 yoke 1. In order to obtain the necessary or sufficient contact and friction between the pin 2 and the heads 4, 4', a pressure screw 3 is inserted into the top of the handle, the lower or inner end of this screw bearing and 45 pressing upon the upper end of the rotary pin.

On opening the compasses, the pin 2 is rotated (by the mediation of its foot, as described and shown) by means of the moved 50 head (4 or 4'), and while being rotated the foot rolls along upon a corresponding portion of the circumference of the other head (4' or 4). Owing to the two heads (4 and 4') moving relatively to one another, it is 55 immaterial which of them is held fast and

which is moved, or whether both legs are drawn apart simultaneously; the motion of the pin foot relatively to the head 4 is equal to its motion relatively to the head 4', so that it adjusts itself automatically into the middle line relatively to the legs of the compasses. 60

As the rotary pin although being positively moved, is not constrainedly moved, it may occasionally get a little out of the 65 proper middle line. To correct such a deviation I have devised two means, of which the one is shown in Figs. 1 and 2, the other in Figs. 3 and 4. In the first instance the yoke 1 is downwardly elongated to below the heads 70 4 and 4', and the two legs of the yoke are connected with each other by a pin or bolt 5, the shank of which lies in oppositely located cavities of the legs if the compasses are closed, as in Fig. 1. Supposing, the handle (inclusive, of course, the rotary pin) has 75 got out of the proper middle line, it is automatically turned back into its proper position by the operator closing the compasses, when the legs will grasp the pin 5 between 80 them and readjust the handle.

In the form of construction shown in Figs. 4 and 5, the yoke 1' is not elongated, and there is, consequently, no such pin or bolt 85 like 5 (Figs. 1 and 2), but each of the heads 4 and 4' has a pin 6, which in the closed position of the compasses contacts with one of the yoke legs. The distance between the axes of the two pins 6 corresponds to the breadth of a yoke leg, and it is obvious that if 90 the handle should have left its proper middle position relatively to the legs of the compasses, this latter need merely be closed when the handle will be automatically readjusted. 95

Having thus particularly described my invention, what I claim as new and desire to secure by Letters Patent of the United States is:

1. A straight-line guide for the handle of 100 compasses, comprising, in combination, disk-shaped heads forming the rotatory ends of the legs of the compasses; a yoke forming the bearing for said heads; a hollow handle forming an elongation of said yoke and a 105 rotary pin in said handle; the lower end of said pin being in frictional contact with said two disk-shaped heads at their circumference, for the purpose set forth.

2. A straight-line guide for the handle of 110

- compasses, comprising, in combination, disk-shaped heads forming the rotatory ends of the legs of the compasses; a yoke forming the bearing for said heads; a hollow handle forming an elongation of said yoke; a rotary pin in said handle; and a frictional contact member forming the lower end of said pin and being in frictional contact with said two disk-shaped heads at their circumference, for the purpose set forth.
3. A straight-line guide for the handle of compasses, comprising, in combination, disk-shaped heads forming the rotatory ends of the legs of the compasses; a yoke forming the bearing for said heads; a hollow handle forming an elongation of said yoke; a rotary pin in said handle and a pressure screw also located in the said handle co-axially with said pin, for the purpose set forth.
4. A straight-line guide for the handle of

compasses, comprising, in combination, disk-shaped heads forming the rotatory ends of the legs of the compasses; a yoke forming the bearing for said heads; a hollow handle forming an elongation of said yoke; a rotary pin in said handle; and a frictional contact member forming the lower end of said pin and being in frictional contact with said two disk-shaped heads at their circumference, said contact member forming an inverted trough, the rim of which is adapted to co-operate with the said disks, substantially as described.

In testimony whereof I affix my signature in presence of two witnesses.

AUGUST RENZELBERG.
